UNITED STATES PATENT OFFICE.

CHARLES E. C. EDEY, OF TACOMA, WASHINGTON.

COMBINED LOCK AND KNOCKER.

1,110,194.

Specification of Letters Patent.

Patented Sept. 8, 1914.

Application filed October 17, 1913. Serial No. 795,769.

To all whom it may concern:

Be it known that I, CHARLES E. C. EDEY, a citizen of the United States, residing at Tacoma, in the county of Pierce and State of Washington, have invented certain new and useful Improvements in Combined Locks and Knockers; and I do hereby declare the following to be a full, clear, and exact description of the invention, such as will enable others skilled in the art to which it appertains to make and use the same.

This invention relates to combined locks and knockers.

Briefly described, the invention involves the use of a latch member which may be locked by a cylinder of the Yale type, this cylinder being mounted in a latch-operating sleeve, which is rotatable from the outer side by means of a thumb member, after the lock is released by inserting a key in the cylinder. The knocker is mounted on a member which also carries the sleeve.

In the accompanying drawings, Figure 1 is a view of the device in front elevation; Fig. 2 is a view in side elevation; Fig. 3 is a detail of the locking mechanism; Fig. 4 is a top plan view of the knocker and of the lock on the inner side of the door; Fig. 5 is a fragmentary view in elevation of a portion of the lock with one plate removed as it is seen by looking toward the left in Fig. 4; Fig. 6 is a view similar to Fig. 5, but with the roll-back removed; Fig. 7 is a detail of the member designed to lock the latch from the inner side of the door; Fig. 8 is a detail of a slotted sleeve for receiving a device for locking the mechanism from the inner side only; Fig. 9 is a detail partly in section showing the device in which the locking cylinder is mounted.

Referring to the drawings in detail, 10 indicates the escutcheon plate of the knocker 12, the latter being pivoted at 15 to the trunnions 16 rigidly mounted on or forming part 45 of the casing 17 which receives the operating mechanism described below. The casing 17 is rigidly connected with plate 10 and within this casing is mounted a sleeve 18 having a slotted portion 19' toward the front end. 50 The locking cylinder 19 is mounted within a cylindrical portion 20 carried by an up-standing member 21 projecting through the aforesaid slot and carrying a thumb-piece 22 by means of which sleeve 18 is operated 55 when the lock is released. Sleeve 18 controls

the latch member 23. In order to effect the control of the latch 23 by means of sleeve 18, said sleeve is provided with a slot 24 which is engaged by a spline 25 on a sleeve 26 operating the roll-back members 27 and 28, 60 the latter being rigidly secured to sleeve 26. Members 27 and 28 engage the forked portions of member 30 comprising the shank to which the latch 23 is secured. In order to permit the operation of the latch, a key is 65 inserted within cylinder 19 of the lock, and this cylinder when rotated operates the square spindle 35 engaging a square socket in cam 36. When this cam is turned to the dotted position shown in Fig. 6, it engages 70 lug 37 of pivoted locking member 38, and throws end portion 39 out of contact with lug 40 carried by shank 30. This releases shank 30 and permits the operation thereof by means of the roll-backs or by means of 75 cam 36, and especially the end 41 thereof. Pivoted locking member 38 may also be operated from the inner side of the door by means of thumb member 42 carrying on its inner end a lug 43 engaging a notched portion 44 of member 38. The lower end 45 of member 38 engages a flat spring 46 mounted on one of the plate members of the lock and holds member 38 in the position in which it has been placed or thrown by the devices 80 above described.

The pin tumblers of the locking cylinder are indicated by 14, in Fig. 1. Pins 35' permit of the operation of shaft 35 by the locking cylinder. The anvil member 9 is located 90 in the usual position, and a spacing member 47 for the plates of the lock is shown adjacent screw socket 48.

In order to lock the mechanism from the inner side of the door only, sleeve 18 is 95 provided with a rigidly mounted collar 55 having a slot 56 therein, and this slot is engaged by tongue 57 of slide or bolt 58 mounted in a guiding device 58' on the inner side of the plate 10. Member 58 is 100 provided with an aperture 59 for an eccentric 60 carried by pin 61. The pin may be arranged for operation by a thumb member from the inner side of the door. A knob for the inner side may be carried by spindle 105 50 rigidly connected with a roll-back device, previously mentioned.

It will be understood that when members 55 and 57 are engaged, latch 23 (acting as a night latch), can not be operated by thumb 110

member 22, but may be operated by inserting a key in cylinder 19 and actuating cam 36 and member 30 carrying the latch.

What I claim is—

3. 1. In a device of the class described, a bolt, a rotary member for operating the bolt, locking means for the bolt, a locking cylinder controlling such means, a pivoted device, and means for mounting the pivoted 10 device and the rotary member, said rotary member carrying the locking cylinder such mounting means comprising a tubular member having oppositely located lugs and an open ended longitudinal slot at one end between the lugs, permitting access to the rotary member.
2. In a device of the class described, a bolt, a latch member carried thereby, mechanism including a rotary device for operating the bolt, a locking cylinder within the 20 rotary device, means for operating the rotary device when released, and means for mounting the latter and for mounting a pivoted member such mounting means comprising a tubular member having oppositely located lugs and an open ended longitudinal slot at one end between the lugs, permitting access to the rotary member.
3. In a device of the class described, a 30 bolt, a latch member carried thereby, mechanism including a roll-back for operating the bolt, a sleeve connected with the roll-back, means including a slotted sleeve for operating the sleeve first mentioned, a locking cylinder within the slotted sleeve, a thumb member immediately above the lock-

ing cylinder, projecting through the slotted sleeve at an angle to its main axis and arranged for rotating the slotted sleeve, a bolt locking device, and means for operating the latter from the locking cylinder.

4. In a device of the class described, a bolt, means including a slotted rotary device for operating the bolt, a thumb member for operating the rotary device, a tubular member for mounting the rotary member, trunnions carried by the tubular member, a pivoted ring-like member connected with the trunnions, said member last mentioned having a portion cut away to permit of such 50 connection and the thumb member being located adjacent to the cut-away portion, a locking cylinder within the slotted rotary device, and means connected with the cylinder for retaining the bolt against operation 55 by the device last mentioned.

5. In combination with a knocker and means including a plate and a sleeve for mounting the knocker, of a latch, means for operating the latch by the rotation of said 60 sleeve, locking means concentric with the sleeve, and an independent locking device for the sleeve mounted on the plate on the side opposite to that on which the knocker is located.

In testimony whereof I affix my signature in presence of two witnesses.

CHARLES E. C. EDEY.
